UNITED STATES PATENT OFFICE.

JOHN W. CHAMPION, OF PUEBLO, COLORADO.

RAIL-CLAMPING DEVICE FOR METAL TIES.

1,350,855.

Specification of Letters Patent.

Patented Aug. 24, 1920.

Application filed February 25, 1919. Serial No. 279,086.

To all whom it may concern:

Be it known that I, JOHN W. CHAMPION, a citizen of the United States, residing at Pueblo, county of Pueblo and State of Colorado, have invented certain new and useful Improvements in Rail-Clamping Devices for Metal Ties; and I do declare the following to be a full, clear, and exact description of the invention, such as will enable others skilled in the art to which it 5 pertains to make and use the same, reference being had to the accompanying drawings, and to the characters of reference marked thereon, which form a part of this 10 specification.

My invention relates to improvements in railway rail-secur ing devices adapted to be employed in connection with the metal ties. In this application I have assumed that a hollow metal tie is employed, there being sufficient space below the top or rail-engaging portion of the tie for the introduction of parts of the rail-secur ing devices. My improvement involves both a rail clamp and a 20 rail brace, the latter to be employed at the outer side of the rail on curves only. Where the track is straight away, or in a straight line approximately, the so-called rail clamp would be employed on both sides of the rail.

In my improvement I utilize both in connection with the rail clamp and the rail brace, a key and a key-keeper, the keeper being so applied that it can not move upwardly after it is positioned in the assembled 30 relation with the other parts; and its upper extremity is bent downwardly over the key, thus locking the latter against upward movement. The rail brace and the rail clamp are each provided with a jaw, occupying a 35 position below the top of the metal tie and adapted to engage the lower surface of the latter to prevent upward movement. Each jaw portion is inserted into an opening in the top of the metal tie far enough to bring 40 it below the lower surface of the top of the tie, and is then turned into its proper position to correspond with the securing-position of the upper clamp or rail brace member of the device, as the case may be.

Having briefly outlined my improvements, I will proceed to describe the same in detail, reference being made to the accompanying drawing, in which is illustrated an embodiment thereof. In this drawing:

Figure 1 is a top plan view of a rail and metal tie, showing my improved rail clamp

and brace in position and arranged in co-operative relation on opposite sides of the rail.

Fig. 2 is a side elevation of the structure, 60 or a view looking at the side of the rail on the rail clamp side, the tie being shown in end elevation.

Fig. 3 is a perspective view of the key.

Fig. 4 is a section taken through the rail 65 and tie where the fastening devices are located.

Fig. 5 is a fragmentary section of the rail and tie, showing the key-keeper in elevation.

Fig. 6 is a fragmentary top plan view of 70 the rail and tie, illustrating the manner of positioning the rail brace, which is shown in the position when the key-keeper must be introduced in order to enter the opening in the tie.

Fig. 7 is a horizontal section taken 75 through the shank of the rail clamp or rail brace, cutting the key and key-keeper, showing fragments of the rail and tie in top plan view.

Fig. 8 is an underneath view of the rail 80 brace, the shank thereof being shown in cross section. This is also a view looking in the direction of arrows 8, Fig. 4.

Fig. 9 is a section taken through the shank 85 of the rail brace, looking downwardly.

The same reference characters indicate the same parts in all the views.

Let the numeral 5 designate the metal tie, which is hollow, as shown at 6, below the 90 top 7 thereof and between the downwardly extending side parts 8. The rail which crosses the tie at right angles is designated by the numeral 9. The top of the tie on opposite sides of the rail is provided with openings, 10, elongated in the direction of the length of the rail and adapted to receive the lower jaw portion, 12, of a rail clamp, 8, or a rail brace, 9, as the case may be, when this jaw portion is properly positioned in the 95 opening or so that the upper rail-secur ing portion, 13, of the rail clamp, for instance, occupies a position at right angles to its normal or rail-secur ing position. Between the part 12 and the part 13 of the rail clamp 100 is located a shank, 14, which is of such diameter as to pass through the opening 10 of the tie, regardless of its position. This shank is for the most part circular, but is made flat on one side, as shown at 15, so that 105 the key-keeper 17 will fit the same when the parts are assembled, as hereinafter more

fully explained. The part 13 of the rail clamp has a relatively short projection, 18, which engages the base, 19, of the rail; and a relatively long part 20, which engages the 5 top of the tie, its outer extremity having a shallow, tie-engaging projection, 21, while the part 18 has a similar projection 22, which engages the base of the rail. The length of the part 20 of the rail clamp is 10 such that it may be bent to cause the part 21 to occupy a relatively lower position when for any reason this may be necessary, as in case the clamp should become worn so that otherwise there would be a tendency to 15 looseness.

Arranged in coöperative relation with the rail clamp or brace, as the case may be, and with the key-keeper, is a key, 23, having an enlarged head, 24, and a downwardly extending wedge-shaped shank or body member, 25, which fits tightly within the opening, 10, in the top of the tie when the parts are assembled, and fills the otherwise vacant portion of the opening when the rail clamp 20 and key-keeper are in position for use. This key-keeper, as illustrated in the drawing, 25 preferably consists of a relatively thin piece of metal having a lower jaw or offset, 26, adapted to engage the under surface of the 30 top of the tie when the parts are assembled. It also has a jaw, 27, arranged in opposing relation to the jaw 26, and adapted to engage the upper surface of the top of the tie. Furthermore, the keeper has a projection, 28, 35 adapted to overlap and engage the base of the rail when the parts are assembled, the jaw 28 being on the opposite edge of the keeper from the jaws 26 and 27.

In applying the rail clamp, the jaw portion 40 12 is inserted lengthwise in the opening 10 of the tie, after which the rail clamp is turned in the direction of arrow *a*, until it reaches approximately the position shown in Fig. 6, when the key-keeper is introduced, 45 this being the only position of the brace which exposes a sufficient length of the opening 10 in any direction for the introduction of the lower jaw portion of the key-keeper, since this portion must pass through the 50 opening 10 in order that its jaw 26 may engage the lower surface of the top of the tie. The section portion of the key-keeper in Fig. 6 is taken on the line 6-6, Fig. 5. As soon as the key-keeper is in place, the rail clamp 55 and keeper are moved in the direction of the arrow *a* (see Fig. 6) until the upper part, 13, of the clamp is in operative position. In this position the opening 10 has a vacant space of considerable size, and adapted to 60 receive the wedge-shaped shank, 25, of the key 23, which is introduced and moved downwardly until all parts are tightly secured. The top portion, 29, of the key-keeper is then bent downwardly into engagement 65 with the top of the key, as best

illustrated in Fig. 2, and the rail clamp is then secured in coöperative relation with the rail and the tie.

As heretofore explained, on straight lines of track these rail clamps are arranged in 70 opposing relation on opposite sides of the rail, but on curves I prefer to employ a rail brace, 9, on the outside of the outermost rail. The lower portion of this rail brace is of precisely the same construction as the corresponding portion, 12, of the rail clamp, and it will, therefore, not be necessary to repeat the description of this portion thereof. The upper part of the brace, or that above the tie, has a shallow projection, 30, which engages the top of the tie, and a similar projection, 31, which engages the base of the rail. Furthermore, this brace extends upwardly, as shown at 32, and its upper extremity is shaped, as shown at 33, to fit the outside part 85 of the ball 34 of the rail, thus affording maximum bracing security to the outer rail on curves.

This rail brace is introduced or applied in the same manner as the rail clamp, and a 90 key, 23, and a key-keeper, 17, are employed in connection therewith, as well illustrated in Figs. 1 and 4.

Having thus described my invention, what I claim is:

1. In combination, a rail, a metal tie engaged by the rail, the tie having an opening adjacent the rail, a rail-holding device having a shank occupying said opening and having a jaw extending inwardly beyond the shank and adapted to engage the tie from below, the device having a rail-base-engaging part above the shank and an opposing tie-engaging part also above the shank and extending outwardly beyond the shank and 105 engaging the top of the tie, the opening in the tie occupied by the shank being elongated in a direction parallel with the rail, a key inserted in the opening and lying alongside the rail, and a keykeeper also inserted in the opening and lying alongside the rail and engaging the key to retain the same, said device having a bracing portion extending upwardly into engagement with the side portion of the ball of the rail. 110

2. In combination, a rail, a metal tie engaged by the rail, the tie having an opening adjacent the rail, a rail-holding device having a shank occupying said opening and having a jaw extending inwardly beyond the shank and adapted to engage the tie from below, the device having a rail-base-engaging part above the shank and an opposing tie-engaging part also above the shank elongated and extending outwardly beyond the shank and having a projecting bearing engaging the top of the tie, said elongated portion being adapted to be bent downward to increase the tension of the opposite portion on the rail, the opening in the tie occupied by 115

the shank being elongated in one direction, and a key inserted in said opening.

3. The combination with a rail and a metal tie, the latter having an opening on opposite sides of the rail, rail clamping devices respectively positioned on opposite sides of the rail, each of said devices having a shank occupying the opening in the tie, a lower jaw extending inwardly beyond the shank to engage the top of the tie from below, an upper jaw extending inwardly from the shank into engagement with the base of the rail, and another jaw extending outwardly beyond the shank and engaging the top of the tie, each opening in the top of the tie being enlarged in one direction, a key inserted therein and a key-keeper also inserted therein and located between the rail-holding device and the key and having portions located respectively above and below the top of the tie to engage the top of the tie on the under and upper faces thereof, the top of the keeper being adapted to be bent down over the top of the key.
4. The combination with a rail and metal tie, having a cavity below the top, of two rail-holding devices respectively arranged on opposite sides of the rail, each of these devices having a shank adapted to occupy a hole formed in the tie, a jaw below the shank engaging the top of the tie from below, a portion above the shank projecting inwardly therefrom to engage the base of the rail and another portion above the shank and extending outwardly therefrom and en-

gaging the top of the tie, each opening in the tie being extended in the direction of the length of the rail, a key inserted in said extension, and a key-keeper located between the rail-holding device and the key and having portions arranged respectively above and below the top of the tie, the top of the keeper being adapted to be bent down over the top of the key.

5. The combination with a rail and hollow metal tie having an opening adjacent the base of the rail on each side, of a rail clamping device located on each side of the rail and having a shank occupying one of the openings in the tie, the said device having a jaw extending inwardly beyond the shank and engaging the top of the tie from below, a portion above the shank and extending inwardly into engagement with the base of the rail, and another portion located above the shank and extending outwardly therefrom and engaging the top of the tie, each opening being extended in the direction of the length of the rail to receive the lower jaw portion of the rail-holding clamp when properly positioned, a key inserted in said opening and a key-keeper also inserted in the opening and having projections respectively engaging the top of the tie, both above and below, the upper portion of the key-keeper being adapted to be bent downwardly over the top of the key.

In testimony whereof I affix my signature.

JOHN W. CHAMPION.
